UNITED STATES PATENT OFFICE.

AURELIUS STEWARD, OF BRIDGEPORT, CONNECTICUT, ASSIGNOR TO THE WHEELER & WILSON MANUFACTURING COMPANY, OF SAME PLACE.

TENSION MECHANISM FOR SEWING-MACHINES.

SPECIFICATION forming part of Letters Patent No. 415,951, dated November 26, 1889.
Application filed August 23, 1889. Serial No. 321,718. (No model.)

To all whom it may concern:

Be it known that I, AURELIUS STEWARD, of Bridgeport, county of Fairfield, State of Connecticut, have invented an Improvement 5 in Sewing-Machines, of which the following description, in connection with the accompanying drawings, is a specification, like letters on the drawings representing like parts.

In sewing-machines, when a seam has been 10 completed and it is desired to remove the material, it is customary to lift the presser-foot, and then with the fingers slacken the needle-thread, so that the same may render freely through the eye of the needle, so as to 15 enable the material to be removed from under the presser-foot without breaking the thread or straining the needle.

Some sewing-machines have been provided 20 with automatic means by which to relieve the needle-thread from tension when the presser-foot is lifted.

The invention herein to be described has 25 for its object the production of means for releasing the stud on which turns the tension device—herein shown as a wheel held between washers and acted upon by a spring, adjustment of which regulates the tension on the needle-thread. To lock and release the said stud I have provided it with a toothed 30 wheel, and co-operating with the said wheel I have provided a slide having a projection to engage a space or notch of the said wheel, the said slide being located, as shown, in a groove in the head of the machine, the said 35 slide being moved to release the toothed wheel only when the presser-foot lifter is turned to lift the presser-bar and presser-foot, the mere rise and fall of the presser-foot, as when the machine is being run to 40 stitch material of varying thickness, not effecting the release of the said wheel and stud.

My invention consists, essentially, in a spindle having fast on it a toothed wheel and 45 loose on it a spring-controlled tension device, and a locking-slide having a projection to engage the said wheel, combined with a presser-foot lifter and a device intermediate the said presser-foot lifter and the said locking-slide to lift the latter to release the said

wheel when it is desired to draw off the thread, as described.

Figure 1 in front elevation represents the head of a sewing-machine provided with my improved tension mechanism; Fig. 2, a section of Fig. 1 on the line *x*; Fig. 3, a detail at the inner side of the cap-plate to show the toothed wheel and part of the locking-slide, and Fig. 4 a detail showing part of the presser-foot bar and the intermediate slide actuated 6 by the presser-foot lifter.

The overhanging arm *A*, (partially shown,) the cap-plate *A'*, the needle-bar *A*², the presser-bar *B*, the presser-foot *B'*, its spring *B*², regulating-nut *B*³, arm *B*⁴, and presser-foot lifter *B*⁵, are and may be all as usual. The cap-plate has a bearing in which is mounted loosely a short spindle *a*, provided between its ends with a shoulder *a'*. At its inner end inside the cap-plate the said spindle has 70 fixed to it a toothed wheel *a*², the said wheel being herein represented as attached by a screw *a*³. The spindle *a*, to the right of the shoulder *a'*, receives upon it loosely a tension wheel or device *b*, of usual construction, which 75 at one side bears against a friction-washer (shown in black) interposed between the wheel and shoulder *a'*. The opposite side of the wheel *b* receives against it, as shown, a washer 2, and next the washer on the spindle is a 80 plate *b'*, acted on by a spring *b*², the force of which is regulated by a nut *b*³, screwed upon the split end *b*⁴ of the spindle. The needle-thread, passed once about the wheel *b*, is held under the desired tension by adjusting the 85 nut *b*³, the wheel turning on the spindle when the machine is being run. I have shown the inner side of the face-plate as grooved, as at 4, to receive a locking-slide *c*, (shown as a thin plate of metal,) slotted near its upper end to embrace the inner end of the spindle, as shown in Figs. 2 and 3, the said slide having a projection 5 to enter one or the other of the notches of the wheel *a*² when the slide is 90 permitted to descend to thus lock or hold the spindle. The teeth of the wheel *a*² are pointed, as represented, to enable the projection 5 to enter readily between the said teeth. The presser-bar is surrounded by an intermediate slide *d*, loose thereon, and having two horns 95

d' d², the horn *d'* being interposed between the presser-foot lifter and the arm or projection *B⁴*, the horn *d²* being extended into the slot 4 under the lower end of the locking-slide. In this way the presser-bar is free to rise and fall according to variations in thickness of material under the presser-foot without affecting the tension; but when the presser-foot lifter is turned to lift the presser-foot for the removal of the work the said lifter first meets the horn *d'* and lifts the intermediate slide and the locking-slide, so that the latter releases the wheel, leaving the spindle free to be rotated by slight strain upon the needle-thread.

5 I claim—

1. The loosely-held spindle having a toothed wheel attached to it and having a spring-controlled tension device loose thereon, combined with the locking-slide *c*, having a projection to engage the said toothed wheel, substantially as described.
- o 2. The loosely-held spindle having a toothed

wheel attached to it and having a spring-controlled tension device loose thereon, combined 25 with the locking-slide *c*, having a projection to engage the said toothed wheel, and with the presser-foot lifter and intermediate slide having horns, substantially as described.

3. The cap-plate having the groove 4, the 30 locking-slide *c* therein having a pin 5, the shouldered spindle mounted loosely in the said cap-plate, the toothed wheel *a²*, the spring-controlled tension-wheel, and the presser-bar, combined with the presser-foot 35 lifter and the slide *d*, guided by the presser-bar and having horns, substantially as described.

In testimony whereof I have signed my name to this specification in the presence of 40 two subscribing witnesses.

AURELIUS STEWARD.
